UNITED STATES PATENT OFFICE

2,482,404

DISK PROJECTILE GAME APPARATUS

Julian Domingo, Baltimore, Md.

Application August 23, 1946, Serial No. 692,543

2 Claims. (Cl. 273—126)

1

This invention relates to a game of competition between two or more players.

An object of the invention is to test the skill of the players in pitching.

Another object of the invention is to provide a game which is educational inasmuch as it trains the eyes of the players in their constant endeavor to achieve a higher score, and also since it teaches the player to examine the results and to give an honest appraisal and judgment thereof.

A further object of the invention is to provide a game in the course of playing which the players derive healthful exercise.

Other objects and advantages of the invention will become apparent from the following description of a preferred embodiment thereof as illustrated in the accompanying drawings, and in which,

Figure 1 is a plan view of the game table.

Figure 2 is a view in side elevation of the game table shown in Figure 1.

Figure 3 is a view in end elevation of the table shown in Figure 2, as seen from the right hand end of the view.

Figure 4 is a plan view in detail of the tanga used in playing the game.

Figure 5 is a plan view in detail of a coin used in playing the game.

Figure 6 is a plan view in fragment of the head end of the game table after a winning pitch has been made.

Figure 7 is a plan view in fragment of the head end of the game table after several pitches have been made, and,

Figure 8 is a plan view in fragment of the head end of the game table after several pitches have been made, showing a different result to be scored.

As seen in the view, there is a table 2, mounted on legs 4 extending into sockets 6 secured to the underside of the table near its four corners. The table is elongated and is preferably rectangular in shape, being substantially ten feet long, three feet wide, and twenty-six inches high according to one preferred embodiment. Two feet from the head end 8 of the table and along the longitudinal center line of the table, is a small disc 10 called the target master, resting on the table surface 11, and on top of the target master 10 is piled a number of coins 12 called the main target 14.

Side rails 16, having their inner surfaces 17 inclined as best seen in Figures 1 and 3, extend along the head end sides of the table. An end

2

rail 19 extends across the head end of the table, its inner surface 21 being inclined or sloping in a manner similar to surfaces 17, and a net cloth 18, inclined as best shown in Figures 1 and 2, is stretched across the head end of the table to act as a back stop and catcher of coins and flying tanga. The player stands one foot from the foot end 23 of the table with his right foot to the line 22 which is marked on the floor underneath the foot end of the table. The player can bend to pitch his tanga 24 but not too far forward to steal any distance to the target. As shown, the tanga are relatively large discs bearing some identification printed thereon, such as alphabetical letters, A, B, and C. It is the aim of the players to separate the pile of coins from the target master either at random or one by one by pitching the tanga in a sliding manner along the surface of the table toward the target. It is apparent that a skillful pitch can be made which will result in the tanga sliding beneath the edge of the lowermost coin in the pile and hitting the target master 10 so as to displace it from position beneath the pile of coins, the tanga taking its place, as shown in Figure 6, which is a winning pitch or perfect shot, and the player doing this wins the game.

Tanga falling in the net cloth or off the side would be out of that round of the game until the player's turn again. Any coin in the main target falling onto the net or off the sides in the same manner is to be returned back on top of the target master wherever it is located on the table.

Figure 7 is a plan view of the field after the two players have played in the first round. The target master 10 is still with the main target. Three coins 12 have been separated from the target with the target master. To decide which player wins these coins the distance is to be measured between each player's tanga. The player whose tanga is the shortest distance from the coin wins that coin. His tanga must be a shorter distance to the coin than from the target master to the coin also in order to win that coin. In the event the separated coin is closer to a coin adjoining or touching the target master, or touching another coin that is in turn touching the target master, the player would not win this coin. As is seen in Figure 7, tanga A wins coin 1, and tanga B wins coin 2. The players must remove whatever they win after approval by the other players. The players then pick up their tanga and continue the game as before.

As shown in Figure 8, in the second round of the game, both tanga A and B are touching the

target. In this case the game is over and the players share the winnings. In other words, the game is a draw.

In the course of the game when any player wins, he must pick up his coins with the approval of his opponents before any other player pitches. After becoming expert a player may allow some less skillful player to use three tanga against his two tanga.

Another rule is that if the target master was hit and separated from the main target, the players measure the distance between the target master and the main target, or separated coins, and between the tanga and the target. If a player's tanga is nearer to the coins than the target master, he wins those coins. In case the target master was hit and separated from the main target and tanga A remained on top of the target, and then tanga B was pitched and rested on tanga A, then tanga A would be the winner because tanga B would not then be touching the target.

Although I have described a preferred embodiment of my invention in specific terms, it is to be understood that various changes may be made in size, shape, materials and arrangement without departing from the spirit and scope of my invention.

I claim:

1. Game apparatus comprising a longitudinally elongated board having a smooth unindented playing surface, a single target spot on said playing surface spaced rearwardly from and adjacent to the forward end of said surface and positioned midway between the sides of said surface, a headrail on said board extending across the forward end of said playing surface and siderails on said board extending rearwardly from said headrail and reaching rearwardly along the opposite sides of said playing surface to points intermediate the forward and rearward ends of said playing surface, the entire lengths of said headrail and siderails having inwardly declining surfaces serving to gravitationally return to said playing surface and toward said target spot projectiles and target disks striking said declining surfaces whenever a projectile is slid forwardly along said playing surface and strikes a plurality of target disks stacked on said target spot with sufficient force to scatter the projectile and the target disks on said playing surface into contact with said declining surfaces.

- 5 2. Game apparatus comprising a longitudinally elongated board having a smooth unindented playing surface, a single target spot on said playing surface spaced rearwardly from and adjacent to the forward end of said surface and positioned midway between the sides of said surface, a headrail on said board extending across the forward end of said playing surface and siderails on said board extending rearwardly from said headrail and reaching rearwardly along the opposite sides of said playing surface to points intermediate the forward and rearward ends of said playing surface, the entire lengths of said headrail and siderails having inwardly declining surfaces serving to gravitationally return to said playing surface and toward said target spot projectiles and target disks striking said declining surfaces whenever a projectile is slid forwardly along said playing surface and strikes a plurality of target disks stacked on said target spot with sufficient force to scatter the projectile and the target disks on said playing surface into contact with said declining surfaces, and a forwardly inclined projectile catching net mounted on said board to project behind and above said headrail at an inclination similar to that of the headrail surface in a position to catch and hold and hold out of play a projectile or target disk moving forwardly along said playing surface with such force as to climb up and over the declining surface of said headrail.
